UNITED STATES PATENT OFFICE.

DANIEL W. NORRIS, OF ELGIN, ILLINOIS.

JAR FOR BUTTER, &c.

SPECIFICATION forming part of Letters Patent No. 319,841, dated June 9, 1885.

Application filed March 23, 1885. (No model.)

To all whom it may concern:

Be it known that I, DANIEL W. NORRIS, of Elgin, in the county of Kane and State of Illinois, have invented certain new and useful 5 Improvements in Jars for Butter &c.; and I do hereby declare the following to be a full, clear, and exact description of the same, reference being had to the accompanying drawings, forming a part of this specification, and to the 10 figures and letters of reference marked thereon.

The deterioration of preserves, butter, and other analogous materials when put up in ordinary jars or cans is due largely to the presence 15 of air within such jars, and while in the canning of vegetables, shell-fish, and other articles put up in a cooked state the exclusion of the air from the cans can be effected by pricking a hole in the filled cans, then placing the cans 20 in a boiler and subjecting them to a degree of heat above the boiling point, and then closing the hole by solder or otherwise, such a process is entirely inapplicable to materials such as butter, where the application of heat is not 25 only not desirable, but decidedly and fatally objectionable.

It is the object therefore of my invention to provide an improved jar or can, from which the air can be excluded by a very simple 30 mechanical manipulation and without the use of heat.

This object I accomplish by combining with a jar which is externally screw-threaded at its mouth, a removable sheet-metal top or cap 35 formed with an inner flange and a screw-threaded outer flange, between which the edge of the mouth of the jar is adapted to be confined, and having a central conical portion provided with a perforation or vent, whereby, whenever said 40 top or cover is screwed upon the jar, the contents of the latter will be displaced by the central conical portion and the air expelled through the said perforation, substantially as will be hereinafter fully pointed out, the perforations being then closed by a drop of solder, to effectually seal the jar.

In the accompanying drawings, Figure 1 represents an elevation of a butter-jar constructed in accordance with my invention, its

upper portion and its cap or cover being shown 50 in section. Fig. 2 is a top view of the same. Figs. 3 and 4 are views of modified forms of tops.

The letter A indicates the body of the jar, made of glass, earthenware, or any other suitable material, and preferably exteriorly screw-threaded at its mouth, as shown.

B represents the top or cap constructed of sheet metal and having an inward flange, b, an outward screw-threaded flange, b', and a 60 raised and conical central portion, b'', provided with an aperture at its apex or highest point b'''.

My design in thus forming and perforating the top is to cause it, when forced down to its 65 seat, to displace the upper portion of the butter and crowd it up toward and to the central perforation and thus drive out the objectionable air from the interior of the jar, the said perforation being then closed by a drop of 70 solder, or in any other suitable manner, as will be readily understood.

Any suitable packing material—such as treated or prepared paper, india-rubber, or other suitable material—may be interposed between the top and the jar, as shown at d in Figs. 1 and 3, and when considerable pressure is required in displacing the butter or other material by the operation of forcing the top to its seat, it may be found desirable to make 80 the inner flange of the top vertical, as shown in Fig. 4, so as to fit the interior of the jar more like a piston. With such a construction there would also be less liability of the material being crowded into the joint between the top and the jar.

For convenience in removing the contents of the jar, the latter is preferably made to taper outward from bottom to top slightly, as shown in Fig. 1.

Butter and other analogous articles put up in jars made in accordance with my invention, wherein all air is practically excluded, will be found to keep much longer in a sweet fresh condition than in jars where an air-space is 95 left beneath the cover.

I claim as my invention—

The combination, with the jar externally

screw-threaded at its mouth, of a removable screw-threaded sheet-metal top or cap having a screw-threaded outer flange and a plain inner flange between which the edge of the mouth of the jar is confined, and having its central portion made conical, with the concavity on the inner side, and provided with a perforation at the apex of the concavity adapt-

ed to be closed by a drop of solder, substantially as described, and for the purpose specified.

DANIEL W. NORRIS.
